UNITED STATES PATENT OFFICE

MELVIN MAXAM, OF BELOIT, OHIO.

FENCE.

SPECIFICATION forming part of Letters Patent No. 393,168, dated November 20, 1888.

Application filed August 13, 1888. Serial No. 282,674. (No model.)

To all whom it may concern:

Be it known that I, MELVIN MAXAM, a citizen of the United States, residing at Beloit, in the county of Mahoning and State of Ohio, 5 have invented certain new and useful Improvements in Fences; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

This invention relates to certain new and 15 useful improvements in fences of that class in which the rails are supported and secured in position by wires; and it has for its object to improve upon previous constructions of this character, and to construct a fence with less 20 parts and with much less trouble in securing the said parts together.

The novelty resides in the peculiar combinations and the construction, arrangement, and adaptation of parts, all as more fully hereinafter described, shown in the drawings, and then particularly pointed out in the appended 25 claim.

The invention is clearly illustrated in the accompanying drawings, which, with the letters of reference marked thereon, form a part 30 of this specification, and in which—

Figure 1 is a perspective view of a portion 35 of a fence constructed in accordance with my invention. Fig. 2 is a vertical section through the line α α of Fig. 1, looking in the direction of the arrow in said figure.

Referring now to the details of the drawings by letter, A designates the stakes which cross each other near the top, as shown, and at their 40 junction they are secured together by means of the wire loop a. The lower ends of these stakes are connected together and braced by means of the wire b, the ends of which are secured, one to each stake, and between the ends 45 of the wire is formed a loop, c, which closely embraces the lapped ends of the lower rails of two adjacent sections.

The top rails are secured as follows: d is a wire, one end of which is passed through the 50 loop a, then back of the crossed ends of the adjacent stakes and around the overlapped ends of the two top rails supported by the crotch of said stakes and by said loop a. The other end of this wire d is secured to the lower 55 one of the overlapped bottom rails at the next

stakes after first passing through the loop c of the wire b, which embraces the said lower rails. By this arrangement the strain on the wire d tends to more firmly bind the parts in their positions, and the liability of the same 60 to become displaced or moved endwise is avoided. This diagonal wire d may be used on every section or on every alternate one, as preferred; but on hilly and uneven ground it will be found best to employ it at every sec- 65 tion.

The rails intervening between the top and bottom rails are secured together and to the top and bottom rails by the wire e, which passes around each rail, and between each rail 70 is twisted, as shown.

A fence constructed as above described will be found to be very strong and durable, and can be easily and quickly put up or taken down. The connection of the diagonal wire 75 d and movement of the parts, either lateral or in the line of the fence, only tends to make the parts more secure.

I am aware that diagonal braces, both of wood and wire, have long been used in fences, 80 and do not seek to claim such construction broadly. I attach special importance to my peculiar manner of connecting the diagonal wire to the top rails and to the stakes, whereby the stakes and the top rails are firmly held together and displacement of the same avoided. 85 Any lateral movement or movement in the line of the fence only tends to more firmly draw the parts together, and the binding-wire a also serves to hold the parts close together. 90

What I claim as new is—

The fence described, consisting of the crossed stakes and the loop embracing the same at their junction, the cross-wire securing the lower ends of said stakes, the said wire being 95 formed with a loop embracing the overlapped ends of the bottom rails, and the diagonal brace-wire, secured at one end to the loop of said bottom cross-wire, and its other end passed through the upper loop and to the rear of the 100 crossed ends of the stakes and secured to the overlapped ends of the top rails, substantially as shown and described, and for the purpose specified.

In testimony whereof I affix my signature in 105 presence of two witnesses.

MELVIN MAXAM.
